TUBING BLEEDER.

1,423,937.

Specification of Letters Patent. Patented July 25, 1922.

Application filed August 8, 1921. Serial No. 490,760.

To all whom it may concern:

Be it known that we, GEORGE C. IRONS and ALBERT LARSON, citizens of the United States, and residents, respectively, of McKittrick, county of Kern, State of California, and Bakersfield, county of Kern, State of California, have invented a new and useful Improvement in Tubing Bleeders, of which the following is a specification.

10 The present invention relates to improvements in tubing bleeders and is particularly designed to be used in connection with deep well pumps, as for instance, oil pumps. Its object is to provide a mechanism whereby 15 the oil or fluid collected in the pump tubing above the liquid lifting means can be drained out of the same directly through an opening in the tubing.

The preferred mechanism by which the 20 present invention is reduced to practice is illustrated in the accompanying drawing in which Figure 1 represents a vertical section through a pump casing and a pump tubing having the bleeder attached thereto, Figure 25 2 a side elevation of a sleeve attachment forming part of the device, Figure 3 a perspective view of a spring used in connection with the device, Figure 4 a transverse section through the casing and tubing along 30 line 4-4 of Figure 1, parts being broken away, Figure 5 a side elevation of a valve controlling device used in the tubing bleeder.

Referring to the drawings in detail, the tube (1), of which only a short portion is 35 shown in the drawing, is part of the tubing of a deep well pump from which it is desired to drain the oil or liquid contained in the same. A corresponding portion of the well casing (2) is shown in the drawing of 40 Figure 1. The tubing (1) has attached thereto a longitudinal housing (3), shown in cross-section in Figure 4, in which the bleeding device is enclosed. This housing accompanies the tubing for some distance 45 and is water tightly secured to the same so that no oil or liquid entering the housing from the tubing can escape from the same except through the valve (6) provided near its bottom. This valve controls an outlet 50 (7) for the tubing and when the valve is

open the oil can drain through the outlet into the space around the tubing.

It appears from the drawing that the housing (3) is separated into two chambers (8) and (9) by a transverse wall (11). The lower one of the chambers, 8, is provided with two vertical slots (12) and (14), arranged vertically above each other and leading into the tubing (1). The upper chamber (9) has two similar vertical slots (10) and (15) leading into the opposite direction, that is, out of the housing into the space between the latter and the pump casing.

The valve (6) is operated by means of a vertical rod (16) guided in the bearings (11) and (17), a stuffing box (18) securing a tight connection around the rod (16) between the two chambers. Lifting the rod removes the valve from its seat and opens 65 the outlet, while lowering the rod reseats the valve and closes the outlet. Several ways are provided for opening this valve, which will be described successively.

The first valve controlling means is a perforated disc (21) secured on the sucker rod (22) and working in conjunction with two pawls (23) and (24). One end of each pawl is pivotally supported on a pin (26) secured to the rod (16) in some convenient manner, as for instance by the set screw (27). From this pivot one of the pawls, (23), extends upwardly into the upper recess (14), while the other pawl extends downwardly into the lower recess (12), both pawls being pressed into their respective recesses by the spring (28), a central loop of which fits on the pin (26) and the two arms of which engage the two pawls. The shape and size of the pawls is such that the nose of at least one of them extends always into the tube (1) under the influence of its spring.

This control works as follows: In the drawing the valve is shown as being open. The disc is in a position where it has just opened the valve by carrying upward the lower pawl (23) and with it the rod (16). Pawl (24) has been forced into the tube (1) by its spring and the upward motion of its 95 100

5 pivot (26). A further upward pull on the 10 pivot (26). A further upward pull on the sucker rod (22) brings the disc (21) in contact with the upper pawl, but striking an inclined plane it only forces the pawl out of the tube against the tension of the spring without affecting the rod (16). As soon as it passes the pawl, the latter is forced back into the tube by its spring until its inclined portion comes in contact with the lower edge 15 (31) of the recess (14), which acts as a stop.

If now the disc (21) is lowered again, the pawl (24) presents to it a flat surface and is forced downwardly with the disc, thereby forcing down the pin (26) and closing 20 the valve. But in moving downwardly the inclined lower surface of the pawl (24) rides on the edge (31) of the recess and is forced out of the tube by the downward stroke. Simultaneously the upper inclined 25 surface of the lower pawl is kept in contact with the upper edge (32) of the lower recess by its spring and, being actuated downwardly by the pin (26), is forced into the tube (1). Thus we now find the valve closed, the upper pawl outside of the tube and the lower pawl extending into the tube. On continuing its downward motion the disc 30 (21) comes in contact with the inclined upper surface of the pawl (23) and forces the same to momentarily withdraw from the tube until the disc has passed, but the passing of the disc does not change the situation otherwise. The disc is now in its lowest 35 operative position. If it is raised again, by raising the sucker rod (22), it bears against the lower flat surface of the lower pawl, carries the same upward until the same leaves the tube under the influence of its inclined upper surface sliding against 40 the upper edge of the lower recess and thereby opens the valve. This is the position from where we started, having thus shown that the valve is under complete control at any time by means of the disc and the two 45 pawls.

To absorb the shock of the rod (16) when coming down, a spring (33) is provided between the valve (6) and a pin (34) penetrating the rod; the valve (6) makes a sliding fit with the rod as indicated in the drawing and the slot (36) engaging the pin (37) insures sufficient play between valve and rod to grant operativeness to the spring. Another spring (38) serves to hold the valve in its open position so that the valve can be closed only by the positive action of the controlling pawl.

A second valve control is provided in the 50 pawls (41) and (42) secured to the rod (16) above the pawls (23) and (24) in the upper chamber of the housing (3) and extending through the two recesses (10) and (15). The operation of these two pawls is exactly the same as that of the lower ones and they 55 are actuated by a sleeve (43) which fits

loosely over the tubing and the housing and may be lowered and raised so as to slide along the pawls (41) and (42) by means of vertical rods (44) extending upwardly from the same and ending into a semi-circular 70 yoke (45) joining the two rods at right angles. The yoke carries a ring (46) to which the sand line held by the operator may be attached. It will be seen that when this device is used the sleeve must first be 75 lowered below pawl (41) and in being raised again it will strike the pawl and thereby open the valve.

A third control is the stationary sleeve 80 (47) which works on the same principle with reference to the pawls (41) and (42), with the only difference that the tube moves and the sleeve is stationary. The sleeve is held in its place by two or more springs (48) interposed between the sleeve and the well 85 casing. This stationary sleeve can be connected with the tubing, if it is desired to change its location or to withdraw it, by means of a stud (49) engaging a vertical slot (51) running into a lateral passage 90 (52). It will be easily understood that by turning the tube the stud can be made to register with the slot (51) let down into the same and then locked in the lateral passage 95 by a slight turn.

While the bleeder is thus particularly described with reference to deep well oil pumps, it should be understood that the scope of the present invention is not thereby limited and that the device can be advantageously used in rotary drills and similar appliances.

We claim:

1. Valve actuating means, comprising a stationary element, a valve stem and sliding 105 means mounted in opposite sides of the stationary element and means associated with the valve-stem adapted to be engaged by the sliding means for actuating the valve and to be disengaged from the sliding means 110 by the stationary element.

2. Valve actuating means, comprising a stationary element, a pawl operatively associated with the valve so as to actuate the same presenting an inclined surface held in 115 yielding contact with the stationary element, the nose of the pawl extending beyond the stationary element, and sliding means engaging the nose for advancing the same while the latter is freed from the engagement by its inclined surface engaging the stationary element.

3. In means for draining a tubing of the character described, a lateral housing secured to the tubing having a drain hole 125 therein, a valve for said hole having a vertical stem thereon, a slot in the housing, a pawl having one end pivotally secured to the valve stem, means for pivotally forcing its other end into the slot and sliding means 130

temporarily engaging the pawl for actuating the valve.

4. In means for draining a tubing of the character described, a lateral housing secured to the tubing having a drain hole therein, a valve for said hole having a vertical stem thereon, two vertically aligned slots in the housing, two pawls having one

end pivotally secured to the valve stem, means for selectively forcing their other ends into the slots and reciprocating means adapted to selectively engage one of the pawls to open the valve and the other pawl to close it.
